DESIGN FOR A NAIL SET OR SIMILAR ARTICLE

William H. Shortell, Greenfield, Mass., assignor to Millers Falls Company, Greenfield, Mass., a corporation of Massachusetts

Application February 17, 1940, Serial No. 90,333

Term of patent 14 years

To all whom it may concern:

Be it known that I, William H. Shortell, a citizen of the United States, whose post-office address is 16 Congress Street, Greenfield, Franklin County, State of Massachusetts, have invented a new, original, and ornamental Design for a Nail Set or Similar Article, of which the following is a specification, reference being had to the accompanying drawing, forming part thereof, in which:

Fig. 1 is a side elevational view of a nail set showing my new design;

Fig. 2 is a front view thereof;

Fig. 3 is an end view looking down from the top of Fig. 2; and

Fig. 4 is a sectional view taken on the line 4—4 of Fig. 1.

The drawing is shaded to show contrasting color.

I claim:

The ornamental design for a nail set or similar article, as shown and described.

WILLIAM H. SHORTELL.
